UNITED STATES PATENT OFFICE.

PETER E. McCUALEY, OF MINNEAPOLIS, MINNESOTA.

GRAPPLE.

1,197,751.

Specification of Letters Patent. Patented Sept. 12, 1916.

Application filed March 16, 1916. Serial No. 84,726.

To all whom it may concern:

Be it known that I, PETER E. McCUALEY, a citizen of the United States, residing at Minneapolis, in the county of Hennepin and State of Minnesota, have invented certain new and useful Improvements in Grapples; and I do hereby declare the following to be a full, clear, and exact description of the invention, such as will enable others skilled in the art to which it appertains to make and use the same.

My invention relates to grapples, especially adapted for use in handling metal barrels or casks; and, to this end, generally stated, the invention consists of the novel devices and combinations of devices herein-after described and defined in the claims.

In the accompanying drawings, which illustrate the invention, like characters indicate like parts throughout the several views.

Referring to the drawings, Figure 1 is an end elevation of a metal barrel to which is applied the improved grapple; Fig. 2 is a view partly in side elevation and partly in section, taken on the line $x^2 x^2$ of Fig. 1; Fig. 3 is a bottom plan view of the grapple and bung removed from the barrel, on an enlarged scale; Fig. 4 is a perspective view of the grapple; and Fig. 5 is a detail view in section, taken on the line $x^5 x^5$ of Fig. 3, on an enlarged scale.

The numeral 1 indicates a metal barrel having in one of its heads, at diametrically opposite points, a relatively large bung 2 and a relatively small bung 3. These bungs, as shown, are in the form of screw plugs having hexagon heads to which a wrench may be applied in securing the bungs to the barrel or removing the same therefrom.

Hard rubber gaskets 4 are interposed between the heads of the bungs 2 and 3 and the barrel to prevent leakage. The central portion of the head of the barrel, between the bungs 2 and 3, is depressed. The barrel shown is of well known standard form and it will be noted that the chime thereof is smooth, affording no means whatsoever for a hand hold in lifting the barrel. Many accidents have occurred, while lifting metal barrels of this type, for the reason that they are hard to hold and are liable to slip, particularly oil barrels.

The improved grapple is formed from a single piece of flat metal and comprises a body 5, foot 6, and a crotch 7, arranged to

straddle either of the bungs 2 and 3. The foot 6 is formed by bending one end of the body 5 laterally and then outward into a plane parallel with said body. The crotch 7 is formed by splitting the other end of the body 5 and spreading the bungs thereof. This end of the body 5 is bent laterally and then upon itself with the crotch 7 diverging in a plane that is offset from but approximately parallel to the plane of the body 5, but considerably closer thereto than the foot 6. The purpose of locating the foot 6 at a greater distance from the body 5 is that it engages the head of the barrel within the depression formed therein, as best shown in Fig. 2. A hand hold 8 is rigidly secured to the body 5 on the opposite side from the foot 6 and crotch 7. It is important to note that the inner longitudinal edges of the crotch 7 are relatively sharp, as best shown in Fig. 5.

In lifting or otherwise handling a barrel, the improved grapple is applied, as shown in Figs. 1 and 2, with the crotch 7 straddling the gasket 4 of the large bung 2 and the foot 6 bearing on the central depressed portion of the barrel head. With the improved grapple thus applied, the gasket straddled by the crotch 7, is compressed and the prongs of the crotch are drawn between the head of the respective bung and the barrel, thus affording a secure hold on the barrel, without danger of slippage or displacement therefrom. Obviously, the crotch 7 will straddle bungs of various different sizes.

The above described invention, while extremely simple and of small cost, has, in actual usage, proven highly efficient for the purpose had in view.

What I claim is:—

1. A grapple of the kind described comprising a body member having a laterally offset portion with a crotch arranged to straddle the bung of the barrel, said crotch diverging in a plane that is offset from but approximately parallel to the plane of said body member.

2. A grapple of the kind described comprising a body member having a laterally offset portion with a crotch arranged to straddle the bung of the barrel, said crotch diverging in a plane that is offset from but approximately parallel to the plane of said body member, and a hand hold on said body member.

3. A grapple of the kind described comprising a body member having a laterally offset portion with a crotch arranged to straddle the bung of the barrel, said crotch diverging in a plane that is offset from but approximately parallel to the plane of said body member, said body member having at its other end a barrel-engaging foot.

4. A grapple of the kind described comprising a body member having a laterally offset portion with a crotch arranged to straddle the bung of the barrel, said crotch diverging in a plane that is offset from but approximately parallel to the plane of said body member, said body member having at its other end a barrel-engaging foot, and a

hand hold on said body member at the intermediate portion thereof.

5. A grapple of the kind described comprising a body member having a laterally offset portion with a crotch arranged to straddle the bung of the barrel, said crotch diverging in a plane that is offset from but approximately parallel to the plane of said body member, the longitudinal edges of the crotch being relatively sharp.

In testimony whereof I affix my signature in presence of two witnesses.

PETER E. McCUALEY.
